SWITCHING MEANS

Ernst Blomquist, Lombard, Ill.

Application April 20, 1931, Serial No. 531,342

11 Claims. (Cl. 175—298)

This application is a continuation in part of my Patent No. 1,908,815, granted May 16, 1933, and relates in general to switches and switching cabinets.

5 In recent years, with the coming into use of higher and higher distribution and transmission voltages and the growing demand for electric service in small communities where electric service was hitherto unavailable, the matter of obtaining a compact and economical distribution center or substation has become a matter of great importance. The function of a distribution center is to receive electric power from a 10 remote source, step or transform it to the voltage suitable for local distribution, and provide suitable tapping connections or busses from which the feeder lines may extend.

High voltage transmission lines in this country generally transmit three phase power. The 20 voltage of the transmission line is stepped down to a suitable distribution voltage by means of three single phase transformers. A fourth transformer is provided as a spare, and suitable switching means are provided for connecting the spare 25 transformer in circuit in lieu of any one of the three transformers that may have become defective or that may require inspection.

This invention relates more particularly to the switching means for substituting a spare transformer for one of the transformers in the main transformer bank, and it is one of the objects of the present invention to provide a switching cabinet for enclosing those switches. I provide a cabinet having an oil bath for the switches on 30 the high voltage side of the transformer bank, thus permitting the use of smaller and cheaper switches than would otherwise be necessary since switches of the type designed for outdoor service if immersed in an oil bath may be used on voltages 35 appreciably higher than that for which they were designed, without any sacrifice in the degree of safety provided.

The switches on the high tension side of the transformer bank are enclosed in an oil tank 40 and the switches on the low tension side of the transformer tank are also enclosed in a tank but are not immersed in oil. The means for operating the switches extends outside of the respective tanks and is fully enclosed adjacent each of the 45 switches. In view of the fact that all of the switching equipment is enclosed, I have provided an interlock arrangement to prevent the inadvertent operation of the wrong switch and also have provided an indicator for showing the position of the respective switches. The interlock

between the transformer selector switches is so arranged that any faulty transformer can be replaced by a spare transformer by first turning the interlock indicator to the proper position to release the switches controlling the particular 5 faulty transformer to be replaced, which operation releases the switches on the high tension side and on the low tension side of the particular transformer. The released switches may then be pushed into the downward position which operation automatically disconnects and grounds the 10 windings of the faulty transformer and connects the spare transformer in its place. The interlock indicator will also serve to indicate which 15 transformer is disconnected. The interlock is so arranged that it is impossible to gain access to any of the switches until the circuit through the transformer bank has been opened at another 20 point, thus rendering operations at the switches perfectly safe. The interlock not only prevents 25 operation at the switches but also prevents the touching of the switch handle of the transformer selector switches until the circuit through the 30 transformers has been opened.

A cover is provided above each switch and to 25 operate the switches the cover must be opened and the switches are then operable by means of an operating rod which is inserted through the open top. The interlock prevents opening the 30 cover above any of the switches until the circuit through the transformer bank has been opened at another point.

One of the novel features of this invention lies in the manner in which the high voltage power conductors are extended into the oil cabinet. 35 According to my invention, standard potheads are used, the potheads being mounted in an inverted position directly upon the oil cabinet. This provides a very simple and effective way for leading the conductors into the cabinet, avoiding the 40 use of porcelain bushings such as are used in standard practice upon high voltage transformers.

The attainment of the above and further objects of the present invention will be apparent 45 from the following specification taken in conjunction with the accompanying drawings forming a part thereof:

In the drawings:

Figure 1 is a simple diagram of the connections at the switching center;

Figure 2 is a sectional view through the high voltage oil switching cabinet, said view being taken along the line 2—2 of Figure 5 with the bulk of the interlocking mechanism omitted;

55

Figure 3 is a plan view of the switching cabinet of Figure 2, with the cover removed;

Figure 4 is a sectional view taken along the line 4-4 of Figure 2;

5 Figure 5 is a top view of the switching cabinet with the sleet cover removed, said view being taken along the line 5-5 of Figure 6;

Figure 6 is a sectional view taken along the line 6-6 of Figure 5;

10 Figure 7 is an enlarged fragmentary top view taken along the line 7-7 of Figure 6;

Figure 8 is a sectional view taken along the line 8-8 of Figure 7;

15 Figure 9 is an enlarged view of the interlocking control lever shown in Figures 5 and 6;

Figure 10 is a sectional view through a modified form of switching cabinet such as is adapted for use on the low voltage side of the transformer bank, said view being taken along the line 10-10 20 of Figure 11;

Figure 11 is a sectional view taken along the line 11-11 of Figure 10;

Figure 12 is a longitudinal sectional view showing a modified form of mechanism for operating 25 the bayonet switches within the switching cabinet, said view being taken along the line 12-12 of Figure 14;

Figure 13 is a sectional view taken at right angles to that of Figure 12, said view being taken 30 along the line 13-13 of Figure 14;

Figure 14 is a sectional view taken along the line 14-14 of Figure 12; and

Figure 15 is a fragmentary enlarged view of the indicating mechanism provided for the mechanism of Figures 12 to 14.

In order to facilitate an understanding of the arrangement of the parts within the switch and fuse cabinet and the function of the various parts, reference may be had first, to Figure 1, 40 showing in diagrammatic form a circuit diagram of the connections at the distribution center. An incoming line 1, which is assumed to be three phase and 33,000 volts, extends through the air brake switches 2 to the fuse and switching cabinet 3. It is, of course, understood that the incoming line may be of any other number of phases or at any other voltage. The line conductors extend through the fuses 4 mounted within the oil cabinet 3, thence to the six bayonet 45 type switches indicated at 5 to 10 inclusive. There are two switches provided for each of the A, B, and C phase transformers as indicated in Figure 1. The shaded part of each of the switches 5 to 10 inclusive indicates the insulating portion 50 of the switch whereas the unshaded part indicates the conducting portion. The circuit from one of the line phase conductors extends from the fuse 4 to the terminal 11 of the switch 5, thence through the conducting segment 12 of that switch 55 to the terminal 13 which is connected to one pole of the A phase transformer. A connection from the same fuse 4 extends to the terminal 14 of the switch 6 and by way of the conducting portion of the switch 6 to the terminal 15 which extends 60 to one pole of the B phase transformer.

Likewise, other line conductors 1 extend 65 through the other switches to the B and C phase transformers. The upper conducting portion 13 of each of the disconnect switches 5 to 10 inclusive is connected to the grounded conductor 20. The lowermost contact 22 of the alternate switches 5, 7 and 9 are connected to one pole of the spare transformer and the similar lowermost contact 23 of the alternate switches 6, 8 70 and 10 are connected to the opposite pole of the

spare transformer. When the switches are in the position indicated, the A, B and C phase transformers are connected in circuit with the high voltage line 1 and the spare transformer is disconnected from the circuit.

The conductors from the secondary or low voltage side of the transformer bank extend to the switching cabinet 28. Within the cabinet 28 are mounted three bayonet type disconnect switches 35, 36 and 37 of a somewhat similar construction to the switches mounted in the cabinet 3. The conductors from the A phase transformer extend to the upper terminal clip 40 and the lower conducting segment 41, respectively, of the disconnect switch 35. One of the three outgoing 10 feeder conductors 43 is connected to the terminal clip 44 of the A phase switch 35. The other two outgoing feeder conductors are connected to the corresponding clip of the other two switches 36 and 37. The clips 45 of the three switches are 15 connected together and extend to one pole on the secondary side of the spare transformer S and the other side of the spare transformer is connected to the conducting portions 46 of each of the switches 35, 36 and 37. 20

With the switches in the position shown, the A, B and C phase transformers are connected in circuit. To replace one of those transformers by a spare transformer, it is necessary to depress the corresponding switches on the high voltage 25 side of the transformer bank and the one corresponding switch on the low voltage side. If it is desired to replace the A phase transformer by the spare S, the switches 5 and 10 within the switching cabinet 3 are depressed as is also the 30 switch 35 within the cabinet 28. The depression of the switch 5 causes the conducting section 12 thereof to bridge the contacts 11 and 22 thus connecting one pole of the spare transformer to the transmission line, and it connects the conducting section 18, which is grounded, to the terminal clip 43, thus grounding one side of the A phase transformer. In a like manner the disconnect switch 10 connects the other side of the spare transformer to the transmission line and 35 grounds the other terminal of the A phase transformer. On the secondary side of the transformer bank, the depression of the disconnect switch 35 disconnects the terminal 41 from the terminal 40 which is connected to the neutral of the system and instead connects the segment 43 thereto, said segment being connected as previously stated to one side of the secondary of the spare transformer.

The uppermost conducting portion of the switch 35 which previously bridged the terminals 40 and 44 now bridges the terminals 44 and 45 thereby connecting the opposite pole of the spare transformer to the outgoing feeder conductor which is connected to the terminal 40 and at the same 40 time disconnecting the opposite side of the secondary of the A phase transformer from the circuit.

Reference may now be had to Figures 2, 3, 4, 5, and 6 showing the construction of the switch and fuse cabinet 3 and the switches and interlocking mechanism therefor. The switching cabinet 3 is made of steel sheet and is mounted upon suitable beams 65. The sheet steel cabinet or tank is suitably reinforced at the corners by 50 means of angle beams 63. Two horizontal cross bars 71 and 72 (Figure 4) are mounted within the oil tank and support the panels 73, 73' and 73'' upon which the switch contacts are mounted. A lower bracket 76 and an upper bracket 75 (Fig- 55

ure 2 are secured to the rear side of the panel section 73 and support an insulator 77 supporting a fuse holder 78.

The fuse 4 of Figure 1 is mounted within the 5 fuse holder 78. Brackets similar to 74 and 75 are mounted at the rear of each of the panels 72' and 73' for supporting insulators 77 for the other two phases of the system. The fuse holder may be of any preferred construction and since 10 it does not, per se, form a part of the present invention the precise construction thereof has not been illustrated. For a further description of the fuse holder reference may be had to my Patent No. 1,887,369, issued November 8, 1932.

15 The lead-in-conductors from the power line extend into the oil switching tank through inverted potheads as previously stated. The pothead 80a for one of the phase conductors is indicated in Figure 2. The pothead is secured to 20 the upper portion of the oil tank by means of suitable bolts extending through flanges indicated at 81. The portion 82 of the pothead is the portion which in the usual use of potheads extends in an upward direction. The lead covered 25 cable 83 extends into the potheads and at the lower end a connection is made to the copper conductor within the cable and a flexible lead indicated at 85 is secured thereto. The sheet metal case or cabinet is provided with an opening 30 86a above each of the fuse holders 78 for permitting the insertion or removal of the fuses with or without the fuse holders 78. A pipe section 91 is mounted upon the top of the cabinet adjacent each of the openings and there is provided a 35 hinged cover 92 hinged at 93 for permitting access to the fuse.

The circuit extends from the conductor 85 to a contact clip which is secured thereto and which is clipped on to the fuse holder 78 for establishing a circuit through the fuse within the fuse holder. The clip is indicated at 86 and has a threaded shank 87 integrally secured thereto. The fuse may be withdrawn from the fuse holder by means of the handle 88 within the pipe section 91, said handle being at the end of an insulator which has fuse gripping means at the opposite end thereof. When the fuse has been removed, the shank 87 may be reached through the opening 86a by means of a rod or other tool having a nut at the end thereof for threading on to the shank. The clip 86 is then pulled out of engagement with the fuse holder 78 to permit withdrawal of the fuse holder. The clip cannot be removed from the tank because it is connected to the flexible conductor 85. It is therefore temporarily placed upon a finger member 89 that is secured to the base of the pothead 82 and the tool is unthreaded from the shank 87 and withdrawn from the tank. The fuse holder may then be withdrawn from the tank through the opening 86a by means of a suitable tool. This procedure may be made necessary by a violent blowing of the fuse which results in a breaking of the glass fuse casing. After the fuse holder has been cleaned it is again inserted in place and the fuse clip 86 is picked up from the finger 89 by means of the tool previously used, and again inserted on the fuse holder. It is necessary to use tools in this operation, rather than the bare hand, because the cabinet is filled with insulating oil which during cold winter weather reaches such a low temperature as to preclude any possibility of using the bare hand for manipulating the clip 86. The finger 89 is provided in order to fix the 75 location of the clip 86 when the same is being

sought by the tool used for placing it on the fuse holder.

A conductor 100 extends from the lower terminal of the fuse holder 78 through the hollow insulator 101 to the terminal clip 11 of the A 5 phase switch 5. A conductor 102 comprising a copper bar connects the terminal 11 with the terminal 14 of the B phase switch 6. The conducting section 12 of the switch 5 is adapted to electrically connect the terminal 11 with the terminal 13 when the switch is in the position shown in Fig. 2 or to connect the terminal 11 with the terminal 22 when the switch blade is depressed.

The switch terminal clip 13 is mounted on an insulator 105 which is secured to the panel section 73, and the lower terminal clip 22 of the switch 5 is supported by an insulator 106 which is mounted upon the panel 73 at the lower end thereof. A flexible conductor 107 connects the upper terminal clip 13 to the lower terminal 108 20 of a pothead 109. The pothead 109 is of standard construction and, like the pothead 82, it is mounted in an inverted position. A lead sheathed cable 110 extends outward from the pothead to one terminal of the A phase transformer thus establishing an electrical connection between the terminal clip 13 and the A phase transformer.

The switch 5 comprises a strip of micarta or other suitable insulating material 115 which extends the entire length of the switch. Contact 30 strips of copper or other suitable conducting material are secured to the insulating strip 115 at the opposite sides thereof as indicated at 116. The contact strips 116 are of a length sufficient to bridge the gap between the contacts 11 and 13 35 or between the contacts 11 and 22. Contact strips 118 similar to the contact strips 116 are secured to the insulating material 115 at a point above the contact strips 116 by an amount slightly less than the full extent of travel of the switch 40 blade in the downward direction when the same is pushed so that the contact strips 116 lie between the contact 11 and the contact 22.

When the switch 5 is depressed so as to establish a circuit between the contacts 11 and 22, the 45 bare insulation 115 lies between the contacts 11 and 13, and the contact strips 116 are in engagement with the contacts 13 and 22. A flexible grounded conductor 120 is connected to the contact strips 118 which contact strips extend to the 50 top of the micarta insulation 115. The flexible conductor 120 connects the copper strips 118 with a grounded copper conductor 121 which extends through the switch cabinet. The bar 115 with the strips 118 on the opposite sides thereof 55 extends upward through an opening in the top of the casing and has a small hole 125 formed therein for manipulating the switch, the upper end being enclosed in a pipe 126 provided with a cover 127 hinged at 128. To manipulate the 60 switch the cover 127 is swung to the open position and a hook at the end of a suitable switch operating stick is inserted into the opening 125 and is manipulated to force the switch downward 65 or upward as the case may be.

The contacts 11, 13 and 22 may be of any desired construction and preferably consist of two spring pressed jaws indicated more particularly at 133 in Figure 4. The switch blade is adapted 70 to slide between the spring pressed contact jaws 130 and a suitable hook or bale 131 is provided at each of the pairs of jaws for retaining the blade between the jaws.

When the switch 5 is depressed, a connection 75

is established from the terminal 11, which is connected to the incoming line, to the terminal 22, which, as will be pointed out hereafter, is connected to one side of the spare transformer. At 5 the same time the contact portion 12 interrupts the connection between the contacts 11 and the contact 13 and the grounded conducting portion 119 comes into engagement with the contacting portion 13 thereby grounding one side of the "A" 10 phase transformer.

The three incoming line conductors 1 for the three phases extend into the switching cabinet through potheads such as the potheads 80a and extend through fuses on mountings 78' and 78" 15 similar to the fuse mounting 78 shown in Figure 2 and then the B and C phase conductors extend to the switches 7 and 9 of a construction identical to the construction of the switch 5. The switch 6, which is opposite of the switch 5, has a 20 flexible conductor extending from its upper terminal clip 13 establishing a connection to a conductor which extends into the switch house through an inverted pothead 125 from which a connection is established to one pole of the B 25 phase transformer.

As may be seen from Fig. 3, the switches 5, 7 and 9 which control the connections to one side of the A, B and C phase transformers, respectively, are mounted on one side of the switching cabinet and the switches 6, 8 and 10, which are mounted on the other side of the switching cabinet, control the connections from the other terminals of the B, C and A phase transformers. The terminals 11 and 14 of the switches 5 and 6 30 are connected together by a copper bar 102 and the corresponding terminals of the switches 7 and 8 are connected together by a similar bar 102' whereas the corresponding conductors of the switches 9 and 10 are connected together by a bar 102".

The lower terminals 22 of each of the switches 5, 7 and 9 are connected together by a strip of copper 140 which is connected by means of a flexible conductor 141 to the lower end of the inverted pothead 142 from which a connection extends to one terminal on the high tension side of the spare transformer. In a like manner the lower terminals 23 of the three switches 6, 8 and 10 are connected by means of a flexible conductor to 45 an inverted pothead as indicated at 143 in Fig. 3, from which pothead a conductor extends to the other terminal on the high tension side of the spare transformer.

It may thus be seen that if the two switches 55 5 and 10 are depressed that the high tension side of the "A" phase transformer will be disconnected from the incoming line and will instead be grounded, whereas the two terminals on the high side of the spare transformer will be connected in place of the "A" transformer. In a like manner if the two switches 6 and 7 are depressed instead of the switches 5 and 10, the "B" 60 phase transformer will be disconnected and the spare will be connected in its place. In a like manner the switches 8 and 9 control the establishment of connection for substituting the spare transformer for the "C" phase transformer. The switches 5 to 10 are mechanically interlocked so as to prevent manipulation of non-corresponding 65 switches at the same time thereby preventing any attempted substitution of the spare transformer for more than one of the three transformers. The interlocking arrangement will be 70 fully described as the description proceeds.

75 The switches 6, 8 and 10 are of a construction

identical to the switches 5, 7 and 9 and the switch contacts for those switches are mounted on suitable panels 145 similar to the panel 73. The panels 73 and 145 are suitably braced by braces 146 and 147.

The switching tank is filled with a high grade insulating oil or other suitable insulating liquid to a level above the top of the fuse holder 78.

An explosion valve 148 is provided in the top portion of the switching cabinet, said valve comprising a pipe 149 of suitable diameter provided with a cover 150 hinged at 151 and maintained closed by a spring 152 which is adjusted to a suitable tension to maintain the cover closed until the pressure within the oil tank exceeds a certain limit whereupon the cover is forced open against the action of the spring. A fine mesh wire screen 155 is provided above the opening 148 to prevent the dropping of foreign material into the oil tank.

20 A description will now be given of the interlocking mechanism for interlocking the various selector switches 5 to 10 inclusive amongst themselves and with the operating mechanism for operating the pole top switches 2. As previously 25 stated each of the disconnect switches is operated by first opening the cover 127 (Fig. 2) and then manipulating the switch by means of a suitable switch operating rod. As will be presently pointed out there are two forms of locking 30 mechanism provided; one form of locking mechanism prevents the opening of the covers such as 127 when the pole top switch is closed and thereby prevents the manipulation of the selector switches, and a second interlock is provided for 35 preventing the inadvertent manipulation of the wrong disconnect switches. A description will first be given of the apparatus for locking the covers 127 to prevent inadvertent manipulation of the switches when the pole top switches 2 are 40 closed, and for this purpose references may be had to Figure 5.

As is well known in the art, the disconnect switches 2 are mounted on top of a supporting tower or similar supporting structure and are 45 adapted to be operated in unison by suitable operating mechanism located at or near the bottom of the switch supporting structure, by means of a rod extending vertically from the operating mechanism to the switches 2. A rotatable pipe 50 62 (Figure 5) which controls the locking of the covers 127 extends from the switching cabinet to the operating mechanism or to one of the levers that control the operation of the gang disconnect switches 2 of Figure 1. A clevis 62 is suitably 55 secured to the end of the pipe 62 and mechanical connections are made between this clevis and the mechanism that controls the switches 2 so that when the switches are operated to their open position the rotatable pipe 62 is rotated to the position shown in Figure 6, whereas when the mechanism is actuated to close the switches the pipe 62 is rotated through 90° from the position shown in Figure 5. The pipe 62 extends to the selector switching cabinet and is supported in a suitable 65 bearing bracket 165 secured to the end pipe member 126 (Figure 5) and another and similar bracket 166 secured to the foremost pipe section. Each cover 127 is mounted on the pipe section 62 as by means of a pair of ears 168 formed integrally 70 therewith and through which the pipe 62 extends. The pipe is freely rotatable with respect to the covers. Each cover 127 is adapted to be manually swung into position above the pipe 176 to close the same, a pair of wing nuts being suitably 75

secured to the pipe section and provided in order to securely hold the cover in position. The wing nuts are indicated at 169 and 170 in Figure 7. Locking lugs 171 are rigidly secured to the pipe section 62 adjacent the respective covers 127 and, when the pipe section is rotated through an angle of 90° in a clockwise direction from the position shown in Figure 8, the locking lugs assume a position immediately above the covers 127 and prevent opening of the covers.

When the pole top switch 2 is moved to the open position, the shaft 62 is rotated to bring the locking lugs into position shown in Figure 8, thereby permitting the opening of the covers 127 as desired. When the pole top switch is in the switch closed position, the shaft 62 is moved through an angle of approximately 90° thus bringing the locking lugs 171 immediately above the covers 127 and preventing the opening of the covers; and thereby preventing manipulation of the selector switch. The covers 127 for the three switches 5, 7 and 9 are mounted upon the locking shaft 62, and the covers 175 of a construction identical to the covers 127 are in a like manner mounted upon a locking shaft 176 similar to the shaft 62. The locking shaft 176 has a crank arm 177 rigidly secured thereto and is connected to the shaft 62 by means of a link 178 and a crank 179 which is rigidly secured to the locking shaft 62 as may be seen in Figures 5 and 6.

The covers 92 (Figures 2 and 5) above the fuses are hinged to freely swing about a shaft 93 by means of two members 181 formed integrally therewith and through which the shaft 93 extends, in the same manner as covers 127 and 176 are mounted to freely swing about their respective shafts. Locking lugs 183 are rigidly secured to the shaft 93 adjacent each of the covers and are adapted to be swung over the covers 92 to prevent opening of the covers, all in the same manner as do the locking lugs 171 previously described.

A crank arm 182 is rigidly secured to the shaft 93 and is connected to the crank 179 mounted upon the shaft 62 by means of a rod 180. When the shaft 62 is swung to the position corresponding to the closed position of the pole top switch, the locking lugs 183 are above the covers 92 and prevent opening of those covers.

A description will now be given of the interlock provided between the various selector switches 5 to 10 for preventing the manipulation of more than one set of selector switches at a time. An interlocking lever 200 extends through the three pipe sections 126 housing the upper portions of the switches 5, 7 and 9, suitable openings being provided in the sides of the pipe sections 126 for the locking lever 200. The locking lever extends through all three of the pipe sections 126 and is housed in pipe sections 202 and 203 between the pipe sections 126, and in a pipe section 201 which enters the first one of the three pipes 126.

The upper portion of the blades 5, 7 and 9 is provided with a notch through which the locking lever 200 rides, the notch in the blade 5 being indicated at 205 in Figure 8. When the locking lever 200 is out of the position shown in Figures 7 and 8 the switch blade 5 cannot be depressed because the locking lever is within the notch 205 in the switch 5.

If the lever 200 is shifted in a manner to be presently more fully described, by an amount sufficient to bring the notch 206 into the space occupied by the notch 205 of the blade 5, it will be

possible to depress the blade 5, said blade moving downward within the notch 206. When this has been done it is of course apparent that the blades 205 will retain the locking lever 200 in position preventing further movement of the locking lever until the blade has been restored to the position shown in Figure 8. A notch 207 similar to the notch 206 is provided in the locking lever 200 adjacent the switch 7, the two notches 206 and 207 being spaced from the respective switches by unequal amounts so that one only of the two notches is in register with a switch blade at a time. When the notch 206 is under the switch blade 5, the notch 207 is spaced from the blade 7 and the blade 7 cannot be depressed, whereas if the locking lever is moved a slight additional distance then the notch 207 will come immediately into position opposite the switch blade 7 thereby permitting manipulation of the switch 7, whereas the notch 206 will have moved beyond the switch blade 5 and the switch blade 5 is again held against motion. If the locking member 200 is moved still further then the notch 207 will advance beyond the switch 7 and that switch will also be locked against motion, whereas the end of the lever 200, that is adjacent the switch 9, will ride past the switch 9 thereby permitting manipulation of the switch 9.

In this manner, as is apparent, only one of the three switches 5, 7 and 9 can be manipulated at a time and when one of the switches is operated into the downward position the other two switches are held locked and likewise the interlock mechanism is also locked in its position.

A crank arm 220 pivoted at 221 is connected to the interlocking member 200 by means of a link 222 so that upon turning the crank arm 220 the locking lever 200 is shifted. An operating handle 225 is welded to the bell crank 220 or may be otherwise rigidly secured thereto so that when the operating handle 225 is actuated the bell crank 220 is turned with the result that the locking lever 200 is manipulated. A hand gripping member 225' is provided for actuating the handle 225.

An arcuate shaped plate 228 having four notches 229 therein is provided for accurately determining the position of the interlocking lever 200 from the position of the handle 225. A V shaped projection 230 is provided on the under side of the lever 225, said projections riding upon the arcuate shaped member 228. When the projecting member 230 rests in one of the notches 229, a corresponding notch in the lever 200 is opposite one of the switch blades, and there is provided a plate having the letters A, B and C marked thereon, the markings and the notches 229 being so spaced as to indicate which one of the switches 5, 7 or 9 is unlocked when the lever 225 is in a position opposite the respective notches.

The arcuate plate 228 is provided with an additional notch 230' and the name plate is provided with a letter "O" opposite the position of the handle when the handle rests at the notch 230'. This indicates that none of the selector disconnect switches 5, 7 or 9 can be operated.

The switches 6, 8 and 10 are provided with an interlocking lever 235 similar to the lever 200, said lever 235 being operated by a bell crank 236 connected to the bell crank 220 by means of a rod 237. When the handle portion 225' is shifted to a position opposite the indicating letter "A", the notch 206 in the lever 200 comes opposite the switch 5, whereas a corresponding notch 75

- in the lever 235 comes opposite the switch 10. Under these conditions the switches 5 and 10 may be operated, whereas switches 7, 9, 6 and 8 are held in a locked position. When the handle 5 225' is in the B position, the switches 6 and 7 are released whereas the other switches are held locked, and when the switch handle is in the C position, the switches 8 and 9 are released whereas the other switches are held locked.
- 10 As previously stated in connection with Figure 1, the selector disconnect switches on the low tension side of the transformer bank are housed in a cabinet 28. The cabinet 28 as well as the switches therein are of a construction such as 15 will be more fully set forth as the description proceeds. The cabinet 28 is located adjacent the cabinet 3 and the switches therein are provided with interlocks identical with the interlocks described in connection with the switches on the 20 high tension side of the transformer bank. The covers 240, of a construction substantially similar to the covers 92, 168, and 175, are mounted upon a rotatable shaft 241 similar to the shaft 62, said shaft being provided with locking lugs 242 similar to the locking lugs 171 for preventing 25 the opening of the covers 240. A crank 245 is secured to the shaft 241 and said shaft is connected by means of a connecting rod 246 to the crank 171, and by means of a connecting rod 178 30 to the crank 179 as shown more particularly in Figures 5 and 6. When the pole top switch 2 is open, the lugs 242 are in a position to permit the opening of the covers 240, whereas when the pole top switch 2 is closed, the lugs 242 are immediately 35 above the covers 240 and prevent the opening of the covers, all in the same manner as was previously described in connection with the covers on the high tension side of the switching cabinet.
- 40 The switches 35, 36 and 37 are interlocked by means of an interlocking member 250 of a construction similar to the lock member 200 and provided with notches in a similar manner. The locking lever 250 is connected to a bell crank 251, pivoted at 252, by means of a link 253 and a rod 254. A pipe section 255 encloses the rod 254, suitable packing being provided for preventing the escape of any lubricant that is introduced into the member 255 to reduce the friction therein. Similar rods and packings are provided for the members that operate the locking levers 200 and 235 on the high tension side of the switching cabinet. The notches in the locking lever 254 for locking and releasing the switches 35, 36 and 37 are 50 spaced similarly to the spacing of the notches in the lever 200 and when the operating handle 225' is in the "O" position all three of the switches are locked whereas when the handle 225' is shifted to the "A" position the switch 35 is released; when 55 the handle 225' shifted to the B position the switch 36 is released; and in the C position the switch 37 is released.
- 60 To replace any phase transformer with the spare it is merely necessary to set the interlock lever handle 225' on the position indicating the transformer to be replaced (A, B or C) and then to push the three switches (two on the high tension side and one on the low tension side) marked correspondingly into the "down" position.
- 70 The switches are of course pushed down by means of a switch hook.
- 75 To change back from the spare transformer to the corresponding phase transformer it is merely necessary to note the position of the interlock control lever 225' and then pull up the three

switches with the corresponding markings into the upper position and thereafter set the interlock control lever 225' to the "O" position.

An interlock is provided for preventing the manipulation of the lever 225' from the "O" position to either the A, B or C position when the pole top switch is closed. A forked crank 260 is secured to the locking shaft 62 and controls the movement of a locking pin 261. The locking pin 261 is arranged to ride freely in a groove 232 in the crank 260 and is guided in suitable guides 263 and 264 secured to the pipe section 126 as may be seen in Fig. 6. When the pole top switch is in the open position, the crank 260 is in the position shown in Fig. 6 and the pin 261 is in its 15 uppermost position. When the pole top switch is operated to the closed position the crank 260 is rotated in a clockwise direction as is seen in Fig. 6, thus allowing the pin 261 to drop downward into the path of movement of a lever 266 20 integral with the lever arm 225. When the lever handle 225' is in the "O" position, the portion 266 is located to the right of the pin 261. The position of the arm 266 as seen in Fig. 9 is the position occupied when the arm 225' is in the 25 "A" position, the dotted line position of the member 266 and 225 being the "O" position of the interlock control lever.

It is thus apparent that when the arm 266 is in the position shown in dotted lines in Fig. 9 30 which is the "O" position of the interlock, and when the pole top switch is closed the pin 261 is dropped downward into the path of movement of the arm 266 and the arm cannot be moved from the "O" position to the A, B or C positions until 35 the pole top switch is opened thereby rotating the crank 260 and raising the pin 261 out of the path of travel of the arm 266. This is of importance for otherwise it might be possible to manipulate the handle 225' to the A, B or C position and leave it there without operating the corresponding switches. If the pole top switch were kept closed and service continued with one of the phase switches unlocked, it might happen that after a long period of time the switch that is un- 45 locked would drift downward. The selector switches are not designed to open the circuit when there is current flowing therethrough and if the selector switch that was inadvertently left unlocked were to drop downward a dangerous and 50 very destructive arc might be generated. The above described interlocking arrangement prevents such an occurrence.

A description will now be given of the selector switches on the low tension side of the transformer bank and for this purpose reference may be had to Figures 10 and 11.

The switch cabinet 28 is constructed of sheet steel and is suitably supported by I beams 269 in any desired manner. Panels 261, 262 and 263, 60 upon which the switches 35, 36 and 37 are mounted, are bolted or otherwise rigidly secured to a top angle beam 265 and to a bottom angle beam 266. The three panels are identical as are likewise the switches supported thereon. The 65 switches 35, 36 and 37 are of the bayonet plunger type and are operated by an upward and downward movement of the switch blade. The blade proper consists of a strip of suitable insulating material of prerequisite mechanical strength and 70 electrical insulating qualities needed, and in the present case comprises a strip of micarta insulation although any other suitable insulating material may be used. The micarta insulation is indicated at 265 and comprises a strip of a length 75

extending the full length of the switch blade. Micarta insulation comprises suitable strip canvas impregnated with a phenol condensation product such as bakelite. Contact strips of copper or other suitable conducting materials are secured to the strip of insulating material 265 along the edges thereof at the desired points where contact is to be made between the various contacts as will be presently set forth. The switch 35 is adapted to slide between a number of sets of contact indicated at 270, 271, 272 and 273.

The contacts comprise a pair of jaws of copper or other suitable conducting material which are spring pressed against the switch blade so as to make good electrical contact therewith. A bail 275 between the jaws 270, and similar bails between the jaws of the other sets of the contacts are provided for preventing the switch blade 265 from shifting out of the jaws and at the same time maintaining the jaws together. The contacts 270 are mounted upon an insulator 271 secured to the panel 261. The other contacts 271, 272 and 273 are mounted upon the similar insulators similarly secured to the panel. Two conductors 277' and 278 extend from the secondary or low tension side of the A-phase transformer to the switch cabinet 28. The conductors 277' and 278 extend to the switching cabinet 28 in a conduit 279. The conductors on the B and C phase transformers likewise extend to the cabinet in conduits 280 and 281 respectively, whereas the conductors from the secondary or low tension side of the spare transformer extend to the switch cabinet in a conduit 282. The conductors 278 extend through a clamp insulator 285 to a terminal clip 286 mounted on an insulator 287 at the lowermost end of the panel 261. A flexible conductor 288 connects the terminal on the insulator 287 with a pair of contact strips 290 secured to the opposite sides of the insulator section of the switch blade 35.

The contact strips 290 ride between the contacts 273 upon the insulator 285 when the switch 35 is in its uppermost position. When the switch 265 is moved downward the contacts 290 disengage with the contacts 273. The lowermost contacts 273 of each of the three switches 35, 36 and 37 are connected together by a bar of copper or other suitable conducting material 292 and constitute the neutral of the system. The bar 292 has the neutral ground conductor 293 connected thereto and likewise has a conductor 294, which is the neutral of the system, connected thereto, said conductor 294 extending outward with the outgoing phase leads as will be more fully explained as the description proceeds. A pair of copper strips 300 are secured to the opposite side of the micarta insulation 265 of the switch 35 at a point between the contacts 270 and 271, said copper strips bridging those contacts when the switch is in the position as shown in Figs. 10 and 11. A conductor 301, which is one of the outgoing phase conductors, is connected to a terminal clip 302 which is permanently secured to the contact 271. When the switch 35 is in the position shown in the drawings a circuit is established from one terminal of the low tension side of the A-phase transformer through the conductor 277' and contacts 270, thence by way of the conducting strips 300 to the contacts 271 to the outgoing phase lead 301.

The conductor 278, which is connected to the other terminal of the low tension side of the A-phase transformer, is connected to the system neutral 292 by means of the flexible lead 288,

contact strips 290 and contacts 273. Similar connections are established from the terminals of the B and C phase transformers. The three outgoing leads 301, 305 and 306 as well as the neutral 294 extend from the switching cabinet through a conduit 310 to the various points of distribution. A similar conduit 311 is provided to carry a set of conductors connected in parallel with the conductors within the conduit 310 should the capacity of the distribution center increase to such a point as to necessitate the replacement of the transformer bank by another bank of a larger capacity. The strip of insulation 265 of the switch 35 extends upward through the top of the cabinet 28 into a pipe 315 and adjacent the top thereof within the pipe it is provided with means for permitting an operating hook to grip the same. This means may comprise a hole such as the hole 125 in the switch 5 shown in Fig. 2. To substitute the spare transformer for the A phase transformer, the cover 240 of the pipe 315 is opened, the pole top switch 2 (Fig. 1) having been previously opened to permit the opening of the cover 240 as has been previously pointed out, and the switch 35 is pushed downward by means of a suitable operating hook, the interlock mechanism previously described having been set to the A position. When this is done the upper insulating portion of the switch 35 moves between the contacts 270, thus disconnecting the conductor 277 from the circuit.

At the same time the conductor strips 300 move downward to bridge the gap between the contacts 271 and 272. A pair of contacts comprising contact strips 320 move downward between the contacts 273. One of the leads 325 from the spare transformer is connected to a bar of copper or other suitable material indicated at 326, which bar is connected to each of the contacts 272 of the three switches 35, 36 and 37 by means of suitable clips indicated at 327. When the conducting portions 300 of the switch 35 are moved downward they bridge the gap between the contacts 271 and 272 and thereby establish a circuit between the outgoing phase conductors 301 and the contact bar 326 which is connected to one terminal of the spare transformer. A conductor 330 extending from the other terminal of the low tension side of the spare transformer is connected to the copper bar 331 which is connected to the contact strips 320 by means of flexible conductors or leads 332. Similar flexible conductors connect the copper bar 331 with the contacts corresponding to the contacts 320 of the switches 36 and 37. When the switch 35 is depressed, the contacts 320 extend into engagement with the contacts 273 thereby establishing a connection between the bar 331, which is connected to one terminal of the spare transformer, and the bar 292 which is connected to the conductor 294 constituting the neutral of the outgoing distribution line.

It is thus apparent that by depressing the switch 35 the A phase transformer is disconnected from the circuit and the spare transformer is connected in its place. In a like manner a depression of the switch 36 or 37 will substitute the spare transformer for the B or C phase transformers. The switches being interlocked by mechanism previously described in connection with Figure 5, it is apparent that it is impossible for an operator to actuate more than one of the three switches at a time. The copper bar 331 is mounted to the side walls of the switching cabinet, being secured in place by means of in-

sulators indicated at 341 and 342 in Figure 10.

As may be seen from Figures 5 and 6, sleet hoods are provided for protecting the interlocking mechanism at the top of the switching cabinet 5 from ice and sleet accumulating thereon and interfering with or preventing the operation of the interlocking mechanism. Each of the sleet hoods comprises merely a sheet metal housing secured above the interlocking mechanism. The 10 sleet hood 350 covers the locking mechanism for the covers 92 above the fuses in the high voltage switching cabinet, whereas the sleet hood 351 covers the switch locking mechanism on the high voltage switching cabinet. The sleet hood 352 15 covers the interlocking mechanism on the low voltage switching cabinet. Each of the sleet hoods is provided with a hinged cover indicated at 352', 353 and 354 for permitting access to the covers 92, 168, 175 and 249.

20 A hinged door (not shown) is provided at the front of the sleet hood 351 for permitting access within the sleet hood to operate the interlock actuating arm 225. The connecting rods, such as the rod 190 and 246 between the respective 25 sleet hoods, are covered by inverted channel shaped troughs for preventing the formation of ice and sleet upon the connecting members. To manipulate the switches or the high tension fuses, it is of course necessary to first open the covers 30 on the respective sleet hoods.

As previously stated, the selector switches within the high voltage cabinet 3 and those within the low voltage cabinet 28 are pulled up or pushed down from one position to another by means of a switch operating stick. In very large installations where the switches are of appreciable size and the contact pressure between the contacts and the switch blades is appreciable the force required for directly operating these switches may 40 become quite large. Since the switches are manually operated it becomes necessary to provide means for reducing the amount of effort necessary to operate the switches. In Figures 12, 13, and 14 I have shown an arrangement for facilitating the operation of such switches, said means comprising a worm drive for moving the switches up or down. The upper end of the switch 5 is provided with a screw threaded shank 403 upon which is threaded a nut 401. The nut is 45 rotatable with respect to the shank and is held against downward movement by a U-shaped strap 402 which is secured to the pipe section 126 in any desirable manner, as by means of sets of bolts 404. The nut 401 is held against upward 50 movement by means of a U-shaped strap 405 which is suitably secured to the strap 402 in any desired manner, as by means of screws 407. It is thus apparent that if the nut 401 is rotated it will 55 impart longitudinal motion to the shank 403 since the nut itself is held against upward or downward movement. It is of course to be understood that the nut is freely rotatable between the straps 402 and 405.

A sleeve 418 is welded or otherwise suitably 60 secured to the nut 401, said sleeve being free of the shank 403 and free of the strap 406. The sleeve extends upwardly from the nut to adjacent the open top of the pipe section 126 and is guided adjacent its upper end by means of an inverted U-shaped strap 411 that is secured to the strap 402 by means of screws 412. The sleeve or pipe section 410 is reenforced at its outer end by means of a plug 415. The outer end of the sleeve 410 70 is adapted to receive the end of a crank whereby 75 the sleeve is turned and to facilitate this action,

a slot 416 is provided in the plug and in the end of the sleeve, said slot receiving the end of a pin in the crank member so that when the crank is turned it will turn the sleeve. Rotation of the sleeve produces a rotation of the nut 401 and a 5 corresponding longitudinal movement of the shank 403 and the switch blade 5.

When the switch 5 is provided with operating mechanism such as above described it is necessary to provide means adjacent the top of the pipe 10 section 126 for indicating to an operator the position of the switch. I have provided such indicating means. A square rod 420 which has been given a helical twist is secured to the blade 5 in any desirable manner, as by means of a bracket 15 419 which is bolted to the switch blade. The rod 420 extends into a sleeve 421 through a square hole in a plug 422 which is secured to the lower end of the sleeve 421. The sleeve 421 is supported at its upper end by means of a bracket 424 20 which is rigidly secured to the pipe section 126, the sleeve being provided at its upper end with a flange 425 which rests on the bracket 424 and has an indicating pointer 426 formed thereon. The flange 425 is rigid with the sleeve 421 and 25 the entire unit is free to rotate with reference to the bracket 424. A stop member 423, secured to the top of the bracket 424 prevents upward movement of the sleeve 421. As the switch 5 moves downward the rod 420 is drawn downward there- 30 with and slides through the square opening in the plug 422 that is secured to the lower end of the sleeve 421. Since the rod 420 has a helical twist and since the sleeve 421 is held against downward movement the rod 420 imparts a rotative move- 35 ment to the sleeve, the extent of movement being determined by the pitch of the helical twist and the extent of downward movement of the blade 5. The rod 420 is twisted to the extent of approximately three-quarters of a turn for its entire 40 length so that for the complete movement of the switch blade 5 the sleeve 421 will be turned to an extent somewhat less than three-quarters of one revolution. It is, however, to be understood that the rod 420 may be twisted to a greater or lesser 45 extent if desired. When the pointer is in the position shown in Figure 15 it indicates that the corresponding phase transformer is connected in circuit and to this extent the connections are indicated by the word "Phase" marked upon the 50 bracket 424. In a like manner, when the pointer has been turned through three-quarters of a revolution, indicating the opposite position of the switch, it will be opposite the word "Spare" which is marked on the bracket 424. 55

In compliance with the requirements of the patent statutes, I have herein shown and described a few preferred embodiments of my invention. It is, however, to be understood that the invention is not limited to the precise 60 constructions herein set forth, the same being shown merely for illustrative purposes.

What I consider new and desire to secure by Letters Patent is:

1. In an electric system, a switching cabinet, 65 a plurality of switches mounted in said cabinet, said cabinet having openings adjacent each of said switches, said switches having projections extending through said openings for operating said switches, tubes surrounding the respective 70 openings and sealed to the cabinet and providing enclosures for the projections, closures for said tubes, hinge means for each of said closures including a common hinge shaft, spaced locking means on said shaft for each of said closures, and 75

common operating means for said locking means.

2. Apparatus for substituting one transformer winding for any one of a plurality of transformer windings that are connected in a circuit, said apparatus comprising a closed cabinet, a plurality of sets of vertically aligned contacts within the cabinet, switch blades for each set of contacts, each switch blade being vertically movable between two extreme positions establishing circuit connections with different ones of the contacts, each of the switch blades extending through the top of the cabinet, closures for the extended portions of the switch blades, covers hinged to the closures for permitting access to the blades, and means for preventing opening of said covers until the circuit through the transformer windings has been opened.

3. Apparatus for substituting one transformer winding for any one of a plurality of transformer windings that are connected in a circuit, said apparatus comprising a cabinet housing a plurality of individually operable switching members, there being at least one switching member for each winding replaceable by the first mentioned winding, each switching member being movable from a normal position in which it maintains a circuit through one of the plurality of transformer windings to an alternate position in which it substitutes a connection to the first mentioned transformer winding for a corresponding connection to one of the other transformers, means for preventing access to any of said switch members when the circuit through said windings is closed, and locking means for preventing movement of remaining switching members to their alternate positions while preselected switching members are in their alternate positions.

4. In a polyphase system wherein a set of single phase transformers is provided for transforming the system voltage and a spare transformer is provided, switching means for substituting the spare transformer in circuit for any one of the other transformers, said switching means comprising a cabinet, and a plurality of individually operable switches in the cabinet, each of said switches including a vertically movable blade and a plurality of vertically displaced contacts for each blade, certain of the contacts of all of the switches being associated with the spare transformer, other contacts of the respective switches being associated with the transformers of the first mentioned set of single phase transformers, means carried by said cabinet preventing access to said switches when the circuit through said transformers is closed, and reciprocal locking means engaging said switches and operable to prevent movement of the switches of more than one phase into their vertically displaced positions at one time.

5. In a polyphase system having a set of single phase transformers for transforming the system voltage, and having a spare transformer, means for switching the spare transformer into the circuit in place of any one of the other transformers, comprising a switching cabinet, a plurality of aligned sets of contacts in said cabinet, switch blade members for each of said sets of contacts, said blade members having locking grooves therein, and common operating means including interlocking reciprocal latching bars engaging in said grooves and providing for selective operation of only certain of said members.

6. In a system of the class described, a switch cabinet, a plurality of laterally extending rows of spaced switch members therein having inde-

pendent vertical movement for selectively engaging vertically aligned switch contacts, the ends of said members projecting through said cabinet, individual enclosure means carried by said cabinet for receiving said ends of said members, 5 covers for said closure means, a hinge shaft for each of said rows of switch members, said covers being hinged on said shafts, and means on said shafts for preventing opening of said covers when the circuit through said switch members is 10 energized.

7. In a system of the class described, a plurality of rows of spaced switch members shiftable vertically for selective engagement with vertically aligned switch contacts, latching grooves in said 15 switch members, laterally reciprocal locking bars for each row of switch members, each of said bars having unequally spaced recessed portions adapted to be selectively aligned with the grooves in said switch members to provide for movement 20 of only preselected ones of said switch members at one time, and means for simultaneously actuating all of said bars.

8. In switching means for substituting a spare transformer for one of a plurality of single phase 25 transformers employed in a polyphase system, a first switching cabinet, switches aligned in a plurality of rows in said cabinet for vertical movement, a second switch cabinet spaced therefrom, a single row of corresponding switches therein, 30 reciprocal latch bars for each of said rows of switches, said switches and bars having cooperating interlocking engagement for preventing movement of said switches, means for actuating all of said latching bars in both of said cabinets 35 simultaneously, and means providing for release of only a preselected switch in each of said rows from said interlocking engagement upon operation of said actuating means to place said selected switches in condition for transformer changing 40 operation.

9. In switching means for substituting a spare transformer for one of a plurality of single phase transformers employed in a polyphase system, a first switching cabinet, switches aligned in a 45 plurality of rows for vertical movement in said cabinet, a second switch cabinet, a single row of corresponding switches therein, reciprocal latching bars for each of said rows of switches, said switches and bars having cooperating interlocking 50 engagement for preventing movement of said switches, means for actuating all of said latching bars simultaneously, and means providing for release of only a preselected switch in each of said rows of switches from interlocking engagement 55 upon operation of said actuating means to place said selected switches in condition for transformer-changing operation, said actuating means being operable into a plurality of independent positions for varying the switch selected in each 60 row of switches in accordance with the transformer to be replaced.

10. In switching means for substituting a spare transformer for one of a plurality of single phase transformers employed in a polyphase system, a first 65 switching cabinet, switches aligned in a plurality of rows for vertical movement in said cabinet, a second switch cabinet, a single row of corresponding switches therein, reciprocal latching bars for each of said rows of switches, said switches and 70 bars having cooperating interlocking engagement for preventing movement of said switches, means for actuating all of said latching bars simultaneously, means providing for release of only a preselected switch in each of said rows of switches 75

from said interlocking engagement upon operation of said actuating means, each of said switches having projecting ends, closure means for said ends carried by said cabinets, and means 5 for preventing access to any of said switches through said closure means to operate the same when the circuit through said plurality of single phase transformers is closed.

11. Apparatus for substituting one transformer
10 winding for any one of a plurality of transformer windings that are connected in a circuit, said apparatus comprising a plurality of rows of ver-

tically aligned contacts, a plurality of switch blades for said rows of contacts, said blades being vertically movable between two extreme positions to establish circuit connections with different ones of said contacts, horizontally movable common locking shafts for the blade in each row of blades, and connecting means movable at right angles to said locking shafts and connected thereto for producing conjoint movement of said shafts. 5

ERNST BLOMQUIST.

10
